UNITED STATES PATENT OFFICE.

WOOLMAN G. WHITE, OF BROOKLYN, NEW YORK, ASSIGNOR TO INTERNATIONAL TYPESETTING MACHINE COMPANY, OF NEW YORK, N. Y., A CORPORATION OF NEW YORK.

LINOTYPE-MACHINE.

1,108,818.

Specification of Letters Patent. Patented Aug. 25, 1914.

Application filed June 16, 1912. Serial No. 704,245.

To all whom it may concern:

Be it known that I, WOOLMAN G. WHITE, a citizen of the United States, residing at Brooklyn, in the county of Kings and State of New York, have invented new and useful Improvements in Linotype-Machines, of which the following is a specification.

This invention relates to improvements in Linotype machines and particularly to the mechanism thereof which controls the delivery of the matrices from the magazine, and the primary object of the invention is to provide relatively simple and effective means for controlling the keyboard according to the position occupied by the magazine, such controlling means according to the present invention operating automatically to lock the keyboard from operation while the magazine is removed or in an inoperative position and unlocking the keyboard automatically when a magazine is placed in operative position, unintentional delivery of one or more matrices from the magazine due to accidental actuation of the keyboard being thereby avoided.

To these and other ends, the invention consists in certain improvements, and combinations and arrangements of parts, all as will be hereinafter more fully described, the novel features being pointed out particularly in the claims at the end of the specification.

In the accompanying drawing: Figures 1 and 2 represent in vertical section the keyboard mechanism of a Linotype machine embodying the present invention, the controlling means for the keyboard being shown in unlocked condition in Fig. 1 and in locked condition in Fig. 2; Fig. 3 is a rear elevation of the controlling device; Fig. 4 is a perspective view of the locking bar or member which is adapted to coöperate with the key bars of the keyboard.

Similar parts are designated by the same reference characters in the several views.

In the practical operation of Linotype machines as heretofore constructed, it frequently happens that while the machine is idle the magazine is removed, finger keys of the keyboard become accidentally depressed or actuated by those attending to the machine and consequently when a magazine is placed in the machine, the power applied to the keyboard mechanism will set into action the escapement actuating mecha-

nism, thereby operating the corresponding magazine escapements and permitting matrices to be delivered from the magazine, thus causing a delay in the operation of the machine. The present invention avoids this objection by providing a keyboard lock which is controlled by the magazine, the keyboard being automatically locked when the magazine is removed, thereby preventing actuation of any of the keys thereof, and the keyboard is automatically unlocked when a magazine is placed in operative condition on the machine.

The preferred embodiment of the invention is shown in the accompanying drawing and will be hereinafter described in detail, but it is to be understood that the invention is not limited to the particular details of construction and arrangement as shown, as equivalent constructions may be used in carrying the invention into practice.

In the present instance, 1 designates a portion of a magazine having an escapement 2 for each magazine channel thereof, each escapement having a projection 3 whereby it is actuated. A portion of the keyboard is shown embodying a key lever 4 for each finger key, each key lever coöperating with a vertically movable key bar 5 and each of these key bars controls a corresponding escapement actuating device. In the construction shown the usual escapement actuating mechanism is used, there being one escapement actuating device for each escapement of the magazine embodying a cam 6 which is pivoted to turn at 7 on a cam yoke 8, one end of the cam yoke being pivoted or fulcrumed at 9 on the toothed bar 10 which is fixed to the stationary part 11 of the machine, and the opposite end of the cam yoke operates upon a vertically movable escapement actuating bar 12, the latter coöperating with the actuating arm or lug 3 of the respective escapement. The cam is mounted to coöperate with a continuously revolving roller 13, each cam, however, being normally held out of engagement with respect to this roller by the bell-crank lever 14 which is pivoted at 15 to a relatively fixed part 16 of the machine frame, and one end of this bell-crank lever coöperates with the key bar 5 while its opposite end engages beneath and normally supports the cam yoke 8. While the cam yoke and cam are held in elevated or inoperative position, the cam

is held from rotation by a pin 17 on the cam which co-operates with a toothed bar 18, the weight of the cam being so distributed that the projection 17 thereon will remain in contact with the toothed bar 18 until the cam yoke and its cam descend, descent of the cam also bringing it into contact with the rotating roller 13, causing the cam to rotate, and owing to the shape of the cam, the cam yoke 10 will be first elevated and then lowered to its initial position, causing actuation of the escapement 2 to deliver a matrix from the magazine. The operation of each cam and cam yoke is controlled by the respective key bar 5 acting on its respective bell-crank lever 14.

One particular form of escapement actuating mechanism has been shown and described as an example, but the invention is not limited in this respect as any equivalent mechanism may be employed for this purpose. The keyboard lock provided by the present invention operates preferably on a suitable part of the keyboard whereby accidental setting into operation of the escapement actuating mechanism is prevented.

In the preferred embodiment of the invention, the keyboard is locked from actuation except when a magazine is in operative position. In the construction shown, the keyboard controlling means embodies a locking bar or member 19 which is supported by a rail 20 the ends of which are secured to the stationary side frames 21. The locking bar or member 19 is mounted at the under side of the rail 20 and is movable in a direction toward and from the row of key bars 5, each key bar having a shoulder or projection 22 which is adapted to abut against the locking bar or member 19 when the latter is in locking position, thereby preventing actuation of any of the key bars, although when the locking bar or member 19 is retracted, the key bars are free to operate. Different means may be employed for mounting and operating the locking bar or member 19. In the present instance, this bar or member is provided with transverse slots 23 and screws 24 are attached to the rail 20 and operate in said slots to guide the locking bar in its movements. Bell-crank levers 25 are also pivoted on an axis 26 toward the opposite ends of the rail 20, one end 27 of each bell-crank operating in a recess or slot 28 formed 45 in the respective end of the locking bar, and a spring 29 operates on each bell-crank producing a normal tendency to shift the locking bar or member into locked position and to retain the same in such position. The bell cranks 25 are controlled by a pair of push rods 30 which are guided to move vertically by the bars 31, the lower ends of these push rods resting on the arms 32 of the bell cranks while the upper ends of these push rods are adapted to be engaged by a suitable

part of the magazine when the latter is placed in operative position. The placing of a magazine in operative position causes depression of the push rods 30, the latter operating on the bell cranks 25 to retract 70 the locking bar or member 19 and to retain the latter in a position which will clear the paths of movement of the shoulders 22 of the key bars, and while the magazine is in such position, the keyboard will be unlocked and 75 may be operated freely. Removal of a magazine, however, will relieve the pressure on the push rods 30, allowing the latter to rise under the influence of the springs 29, the locking bar or member 19 being simultaneously and automatically shifted into the paths of movement of the shoulders 22 of the key bars, thereby locking the keyboard from operation. The keyboard will remain locked until a magazine is placed in position on the 85 machine, the placing of a magazine in position causing depression of the push rods 30 as before stated, and the keyboard is then automatically unlocked.

What I claim is:—

1. In a linotype machine, the combination of a keyboard mechanism, a removable matrix magazine, escapement mechanism actuated by said keyboard mechanism for controlling the delivery of matrices from the 85 magazine, and means controlled by the position occupied by the magazine for locking the keyboard mechanism from operation.

2. In a linotype machine, the combination of a keyboard mechanism, a removable matrix magazine, escapement mechanism actuated by said keyboard mechanism for controlling the delivery of matrices from the magazine, and locking means controlled by the magazine for preventing operation of 105 the keyboard except while the magazine is in operative position.

3. In a linotype machine, the combination of a keyboard mechanism, a removable matrix magazine, escapement mechanism actuated by said keyboard mechanism for controlling the delivery of matrices from the magazine, locking means to prevent actuation of the keyboard mechanism, and means for automatically causing said locking 110 means to lock the keyboard mechanism from operation when the magazine is removed from operative position and for causing said locking means to unlock the keyboard mechanism when the magazine is placed in 120 operative position.

4. In a linotype machine, the combination of a keyboard mechanism, a removable matrix magazine, escapement mechanism actuated by said keyboard mechanism for controlling the delivery of matrices from the magazine, and locking means normally tending to prevent actuation of the keyboard mechanism and restrained by the magazine while the latter is in operative position.

5. In a linotype machine, the combination of a keyboard mechanism, a removable matrix magazine, escapement mechanism actuated by said keyboard mechanism for controlling the delivery of matrices from the magazine, locking means normally tending to lock the keyboard mechanism from operation, and means operative automatically by a magazine when placed in operative position to retract the locking means and permit

actuation of the keyboard and automatically causing the locking means to lock the keyboard when the magazine is removed.

In testimony whereof I have hereunto set my hand in presence of two subscribing witnesses.
